UNITED STATES PATENT OFFICE.

H. CLAY BASCOM, OF TROY, TOBIAS S. HEISTER, OF LANSINGBURG, AND
CYRUS A. HODGES, OF TROY, NEW YORK, ASSIGNEES TO SAID BASCOM.

DESIGN FOR A COOKING-STOVE.

SPECIFICATION forming part of Design No. 15,397, dated September 16, 1884.

Application filed June 17, 1884. Term of patent 7 years.

To all whom it may concern:

Be it known that we, H. CLAY BASCOM a citizen of the United States, residing in the city of Troy, in the county of Rensselaer and State of New York, TOBIAS S. HEISTER, a citizen of the United States, residing in the village of Lansingburg, in said county and State, and CYRUS A. HODGES, a citizen of the United States, residing in said city of Troy, said county and State, have jointly invented and produced a new and original Design for Cooking Stoves and Ranges, of which the following is a specification, reference being had to the accompanying print, cut, or engraving representing said design.

This design embraces several new and distinct parts and combinations of parts which go to make up the whole design, as shown in the accompanying illustration, and hereinafter specified.

One feature of this design is the shape and ornamentation of each of the doors and panels A B' C D E, consisting of the rectangular outer border, *a*, the serrate rectangular inner border, *b*, and the intervening curved surface, *c*, having the drop-form corner ornaments, *d*, and lateral scroll-form ornaments *e*.

Another feature is the ornamentation of the rectangular panel-plate F for the door A, consisting of the name-band *f*, central sub-circular ornamented portion, *g*, and the pairs of sub-oval end ornaments *h*.

Another part is the ornamentation of the oblong rectangular panel-plate G for the door B or B', consisting of the middle oblong ornamented portion *i*, having angular ends, and the two end ornaments *j*.

Another part is the shape and ornamentation of the oblong rectangular panel-plate H, for each of the raised oblong rectangular panels C D E, as shown in the accompanying illustration.

Another part is the shape and ornamentation of the rear extension-plate, I, consisting of the raised rectangular panel E, curved border *l*, and compound ornament *k*.

The shape and ornamentation of the shelf-supporting plate J consists of the end ornaments *m* and the three compound ornaments *n*.

The design for the front door, K, is distin-

guished by the curved upper portion, *o*, having the four mica lights *p* and top ornaments, *q*, and the lower flat part, *r*, having the six draft-openings *s*, and intermediate ornaments, *t*.

The ornamentation of the lower front plate, L, consists of the compound ornament *w*, on the panel-surface *u*, surrounded by the border-molding *v*.

The design for the legs consists of the convexly-curved surface *x*, having the two border-moldings *y y'* and the compound ornament *z*.

The whole design embraces the shape and ornamentation of the top shelf and its supporting-plate J, the stove-top, the front, including the front hearth, door K, and plate L, the side, including its upper and lower hearths and the doors, panels, and plates A B B' C D E F G H I, and the legs M.

We claim as new—

1. In a design for a stove, the shape and ornamentation of each of the doors or panels A B B' C D E, consisting of the parts *a b c d e*, as shown and described.

2. In a design for a stove, the ornamentation of the oblong rectangular panel-plate F, consisting of the parts *f g h*, as shown and described.

3. In a design for a stove, the ornamentation of the oblong rectangular panel-plate G, consisting of the parts *i j*, as shown and described.

4. In a design for a stove, the ornamentation of the oblong rectangular panel-plate H, as shown and described.

5. In a design for a stove, the ornamentation of the rear extension-plate, I, consisting of the parts *E l k*, as set forth.

6. In a design for a stove, the shape and ornamentation of the shelf-supporting plate J, consisting of the parts *m n*, as shown and described.

7. In a design for a stove, the shape and ornamentation of the front door, K, consisting of the parts *o p q r s t*, as set forth.

8. In a design for a stove, the ornamentation of the lower front plate, L, consisting of the parts *w u v*, as shown and described.

9. In a design for a stove, the shape and or-

namentation of the legs, consisting of the parts $x y y' z$, as shown and described.

10. The design for a cooking-stove, consisting of the top shelf and its supporting-plate, the stove-top, the front, the side, and the legs shaped and ornamented as shown and described.

In testimony whereof we hereunto set our

hands, in the presence of two subscribing witnesses, this 14th day of June, 1884.

H. CLAY BASCOM,
TOBIAS S. HEISTER,
CYRUS A. HODGES.

Witnesses:

CHARLES H. BENEDICT,
CHESTER BASCOM.
